CARL GUSTAF THURE THELIN, OF STOCKHOLM, SWEDEN, ASSIGNOR TO ARTHUR EDWIN KRISTOFER SPÅNGBERG, OF STOCKHOLM, SWEDEN.

STARTING DEVICE FOR INTERNAL-COMBUSTION ENGINES.

1,344,739.

Specification of Letters Patent.

Patented June 29, 1920.

Application filed December 2, 1918. Serial No. 264,979.

To all whom it may concern:

Be it known that I, CARL GUSTAF THURE THELIN, a subject of the King of Sweden, residing at Stockholm, in the Kingdom of Sweden, have invented a new and useful Improvement in Starting Devices for Internal-Combustion Engines, of which the following is a specification.

The present invention relates to a starting device for four-cycle internal combustion engines, such as for instance Diesel engines, of the type which are started by means of compressed air or another pressure agent, and which are provided in ordinary manner with a regulating shaft driven by the crank shaft of the engine and on which cams or cam disks are secured which serve for operating the various valves of the engine, such as starting, suction, fuel and exhaust valves. For the purpose of starting engines of the said kind the compressed air, or the pressure agent otherwise used, must be introduced into at least one of the cylinders of the engine during the period of expansion in said cylinder, which period thus also constitutes the starting period. In ordinary engines of this type provided with 1 to 5 cylinders, however, the said starting periods can not follow so closely on one another that there will always, that is to say, at all positions of the crank shaft, be one cylinder ready for starting in one direction of movement or in both directions. Hence, when the engine has stopped with its crank shaft in a position unfavorable for starting, it is often necessary to turn the crank shaft by hand so that one of the cylinders becomes ready for starting.

To render such turning of the crank shaft unnecessary, it has already been proposed for initiating the starting to turn the regulating shaft of the engine relatively to the crank shaft. In this manner it is thus possible to change the period of the cylinder in which compressed air is first to be introduced for the purpose of starting, to period of expansion, in case the said cylinder is in the period of suction corresponding to the desired direction of movement.

In the accompanying drawing Figure 1 is a diagram of the cranks of a three-cylinder engine, and Figs. 2 and 3 illustrate by way of example a suitable embodiment of the present invention, Fig. 2 showing the

clutch of the starting device disengaged, 55 and Fig. 3 showing the clutch thrown in.

If, in the instance of a three-cylinder engine the crank shaft of which has stopped in the position illustrated in Fig. 1 of the attached drawing, starting is to be effected 60 in the direction of the arrow shown adjacent the crank 1, but the cylinder corresponding to the said crank is in the period of suction, its suction valve thus being open, the regulating shaft is first turned half a 65 rotation. By this turning the period of the cylinder corresponding to the crank 1 is changed from suction to expansion during which latter period the starting valve may open during a certain angle when the crank 70 has passed the upper dead point, for the purpose of admitting into the cylinder the compressed air used for the starting. The said turning of the regulating shaft having 75 been effected, the starting valve is rapidly put into operation by means of a special device which is also used for disconnecting the said valve when the ignition has taken place in the engine. Again, if the engine is to be started, for instance, in the direction of the 80 arrow shown adjacent the crank 2, and if the corresponding cylinder is not in the period of expansion, the same course of operation as above described is followed.

The purpose of the present invention is 85 to provide a starting device by means of which the said turning movement of the regulating shaft may be effected in a convenient and safe manner. The invention consists broadly in this that the regulating 90 shaft supporting the cam-disks is connected with a special device for turning the same relatively to the crank shaft after disengagement of a clutch connecting said two shafts, said device coöperating with the clutch in 95 such manner that on disengagement of the clutch said device becomes connected with the regulating shaft, but becomes disconnected from said shaft when the clutch is thrown in.

The crank shaft 4 is connected by means of a toothed gearing 5, 6, 7 with the regulating shaft. This shaft is divided into two portions 8 and 9 the former 8 of which is driven by the crank shaft 4 by means of the 105 said gearing. On the second portion 9 which is placed in alinement with the portion 8, the cam disks 10 are secured which operate

the valves of the engine. The portion 8 of the shaft is provided with a clutch disk 11, and the portion 9 carries a corresponding clutch disk 12, the said two disks being located opposite one another and provided with holes 13 for two or more clutch studs 14 secured to a sleeve 15 movable longitudinally on the portion 9, so that by moving the sleeve 15 the studs 14 may be moved through the holes in the disk 12 into or out of the holes in the disk 11, when the holes in the said disks are opposite one another which takes place, in the embodiment shown, at every half turn of a rotation of one of the shaft portions relatively to the other. A helical spring 16 is placed around the portion 9 the said spring tending to push the sleeve 15 to the left in Figs. 2 and 3 and thus to move the clutch studs 14 into engagement with the holes in the disk 11. The moving of the sleeve in the opposite direction for disengaging the clutch is effected by hand by means of a lever 17. A beveled gear wheel 18 is secured to the sleeve 15 the said gear wheel being moved, when disengaging the clutch, into engagement with a second beveled gear wheel 19 secured to the shaft of a hand-wheel 20 journaled in a stationary support, the said hand-wheel serving for turning the portion 9 of the shaft when the clutch has been disengaged.

When it is desired to turn the portion 9 of the regulating shaft together with its cam disks relatively to the portion 8 of the shaft geared to the crank shaft 4, it is thus only necessary by means of the lever 17 to disengage the clutch 11—14, the portion 9 becoming geared to the hand-wheel 20 whereby it is now possible to turn the portion 9 half a rotation for producing the desired change of period. When the lever is released the clutch is automatically thrown in and the hand-wheel 20 is simultaneously disconnected from the portion 9 of the shaft.

The embodiment illustrated may of course be modified in several respects without departing from the principle of the invention. If for instance the clutch between the two portions of the shaft is provided with more than two studs, these studs are to be placed at such distances from one another that the clutch members may be thrown into engagement only at every half rotation of the shaft portion 9. Finally, it is not necessary, of course, to divide the regulating shaft into two portions, but the gear wheel 7 may instead be loosely mounted on the shaft, and it may be combined with a device for connecting it to the shaft in different positions, or the gearing 5—7 may be arranged in other manner so that the crank shaft and the regulating shaft may be disengaged from the connection with one another for the purpose of turning the regulating shaft.

I claim:

1. In a starting device for four-cycle internal combustion engines of the type started by means of compressed air or the like, the combination with a crank shaft, of a regulating shaft, a gearing interposed between said crank shaft and said regulating shaft, cams on said regulating shaft for operating the various valves of the engine, a clutch between said crank shaft and said regulating shaft said clutch enabling said shafts to be connected to one another in different angular positions, and a device connected with said regulating shaft for turning the same relatively to said crank shaft, said device coöperating with said clutch in such manner that it is connected to said regulating shaft when the clutch is disengaged but is disconnected from said shaft when the clutch is thrown in.

2. In a starting device for four-cycle internal combustion engines of the type started by means of compressed air or the like, the combination with a crank shaft, of a regulating shaft, a gearing interposed between said crank shaft and said regulating shaft, cams on said regulating shaft for operating the various valves of the engine, a clutch between said crank shaft and said regulating shaft said clutch enabling said shafts to be connected to one another in different angular positions, and a device connected with said regulating shaft for turning the same relatively to said crank shaft, said device comprising a gear wheel movable on said regulating shaft and connected with said clutch, a second gear wheel located so as to be engaged by said first-mentioned gear wheel when moved for disengagement of said clutch, and a hand wheel connected with said second gear wheel.

3. In a starting device for four-cycle internal combustion engines of the type started by means of compressed air or the like, the combination with a crank shaft, of a regulating shaft divided into two portions, a gearing interposed between one of said portions and the crank shaft, cams on the second portion of said regulating shaft for operating the various valves of the engine, a clutch between said two portions of said regulating shaft said clutch enabling the said portions to be connected to one another in different angular positions, and a device connected with said second portion of said regulating shaft for turning the same relatively to the first portion, said device coöperating with the clutch in such manner that it is connected to the said second portion when the clutch is disengaged but is disconnected from said portion when the clutch is thrown in.

CARL GUSTAF THURE THELIN.
